UNITED STATES PATENT OFFICE

JOHN H. VOSS, OF BERWYN, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed October 19, 1931. Serial No. 569,610.

This invention relates in general to telephone systems, but is more particularly concerned with small intercommunicating or private branch systems, especially of the trunk connected type, and the object of the invention, briefly stated, is the provision of new and improved circuit arrangements which are particularly suitable for use in such small systems, and which tend to reduce the cost of manufacture and installation of such systems.

One of the features of the invention relates to the means for enabling a local subscriber to dial ring a plurality of signals common to all the local lines over a pair of common talking conductors, which are normally connected to each local line for telephone intercommunication, to code-ring a desired local subscriber by long or short rings or a combination of both.

Another feature relates to the circuit arrangements whereby each local subscriber is enabled to act in the capacity of an attendant operator to at will connect with any one of a plurality of outgoing trunk calls to originate or answer trunk calls, and to transfer such calls to another local subscriber by calling the desired subscriber over the common talking conductor and requesting such party to answer the call on a certain trunk line which is multiplied between all of the local subscribers' lines.

The foregoing and other features not specifically mentioned may be described more in detail by referring to the accompanying drawing which shows by means of the usual circuit diagrams a sufficient amount of apparatus to enable the invention to be described and understood.

In the drawing, Fig. 1 shows the equipment individual to the local subscribers' lines S and S', one intercommunicating trunk or common talking line comprising conductors 4 and 5, and two interoffice trunks comprising conductors 35 to 38, inclusive, which are multiplied between all the local subscribers' lines over conductors 25 to 28, inclusive. The two local subscribers' lines S and S', as shown, are equipped with a standard and well-known monophone telephone. Attached to the base

on each standard monophone set is a sub-base, such as SB shown in the dotted rectangle, having a spring assembly and keys for operating the same when making or receiving interoffice trunk calls. The sub-base of these subscribers' lines, such as S, have only two keys, one for each trunk line, while the sub-base of subscriber S' has three keys, one for each trunk line and a third key to enable this subscriber to disconnect all the local intercommunicating subscribers, such as S, from the trunk multiples of the interoffice trunk lines to provide secret service for subscriber S'. In a system of this type only one local subscriber, preferably an executive, would be provided with a three-key sub-base while all the remaining local subscribers would be provided with a two-key sub-base, it being understood that all the remaining local subscribers' lines are multiplied to the common talking conductors 4 and 5 and the trunk multiples 25 to 28, inclusive, in the same manner as subscriber S. A push button is also provided in each sub-base for flashing an operator in case the trunk line terminates in a manual telephone exchange, and for cancelling dialled digits in case the trunk lines extend to an automatic telephone exchange.

The mechanical construction of the spring assembly and keys in the sub-bases diagrammatically illustrated in the drawing is shown in the co-pending application of H. F. Oberfell, Serial No. 536,424, filed May 11, 1931. Since the sub-bases of the subscribers' lines, such as S and S' are somewhat similar, the keys and spring assemblies in the sub-base associated with subscriber S' alone will be described. When the hand telephone set is removed from the cradle, springs 154 automatically close. If either key TRK #1 or key TRK #2 is depressed, the bar 161 slides in a horizontal direction, and by means of bushings 162, 163, and 164 operates springs 151, 152, 156, 157, and 158. Springs 155 are operated only when key TRK #2 is depressed. A mechanical lock (not shown) is provided for preventing either the key TRK #1 or key TRK #2 from being operated when the other is operated. The catch bar 160 is operated responsive to the removal of

the handset from the cradle to position itself so that when springs 152 and 155 are operated the same will be mechanically locked until the handset is replaced on the cradle irrespective of the subsequent operations of the keys. The key SS controls only springs 159. The three keys or levers are moved off center and remain in such position until moved by hand back to their normal positions or until the handset is replaced on the cradle, which automatically return the keys to their normal positions. The push button PB controlling springs 150 is of the self-restoring type and operates the springs 154 only as long as the push button is depressed.

Relays 11 to 14, inclusive, are provided in order to enable the local subscribers to dial ring or operate the common call signals 21, 21', etc., which are located at various points throughout the system. These relays are individual to the common talking conductors 4 and 5. Associated with the two trunk lines are shown bells 42 and 43 which produce different tones when operated by ringing current from the main exchange to enable the local subscribers to answer on the proper trunk line. In addition to this signalling arrangement, or in place thereof, alternating current relays 33 and 34 are bridged across the trunk lines and are operated by ringing current transmitted from the main exchange to light a plurality of different colored lamps throughout the system to enable the local subscribers to answer the trunk calls on the proper trunk lines. All of the relays shown are mounted in a small terminal block while the various signals shown are mounted at various positions throughout the establishment where the subscribers may readily hear or see such signals.

Fig. 2 diagrammatically illustrates the manner in which a system of this type will receive its operating and talking battery. In Fig. 2, the conductors 79 and 80 connect the local commercial source to a rectifier or battery eliminator 81, which produces the proper amount of direct current for operating and talking purposes. The rectifier or battery eliminator may be of any well-known or standard manufacture which produces the proper voltage. In case the battery-feed is to be supplied by a rectifier or battery eliminator the negative battery terminal 89 is connected to the rectifier by way of the fuse, terminal 84, and terminal 83, while the positive terminal 90 is connected by way of terminal 87 and terminal 88 to rectifier 81. In case dry cells or batteries are to be used in place of a rectifier, the negative terminal 89 and positive terminal 90 are connected by way of terminals 84, 85, 86, and 87 to the battery 81'. It will be understood that wherever battery is diagrammatically illustrated in Fig. 1 the negative battery terminal 89 is in reality connected to such battery symbol.

The same is also true with respect to the positive battery terminal 90 and the various ground symbols throughout Fig. 1.

Talking battery is supplied from the main exchange on trunk connections while the talking battery for local connections extends through a winding of line relay 11 and ground.

Having described the equipment and apparatus, a detailed description of the operation will now be given. For this purpose, it will be assumed that subscriber S desires to call subscriber S'. In order to call subscriber S', subscriber S will remove the hand set from the cradle and dial digits 8 and 2 in order to operate the common signals 21, 21', etc., to code-ring subscriber S' with one long ring followed by a short ring. Responsive to the removal of the handset from the cradle, a circuit may be traced for energizing the common line relay 11 as follows: from grounded conductor 5, normally closed spring in engagement with spring 56 and said spring, conductor 3, normally closed springs 50, controlled by push button PB, conductor 1, through the substation circuit to conductor 2, spring 51 and its normally engaged spring, conductor 4 and through the winding of line relay 11, to battery.

Subscriber S is, therefore, connected to the common talking conductors 4 and 5 responsive to the removal of the handset from the cradle. In response to the operation of the calling device CD for the first digit, in this case digit 8, the common line relay 11 is intermittently deenergized and energized in accordance with the number of impulses transmitted by the calling line. Upon the first deenergization of line relay 11, said relay at armature 15 and its working contact closes an obvious circuit for energizing slow-to-release relay 12. Relay 12, upon energizing, at armature 16 prepares a circuit for energizing slow-to-release relay 13. On the first deenergization of the line relay 11, the circuit for energizing slow-to-release relay 13 is completed at armature 15 and its back contact. At armature 17 relay 13 prepares a circuit for energizing slow-to-release relay 14, which is completed on the next energization of line relay 11. It should possibly be mentioned that relays 12, 13, and 14, due to their construction, will not release between impulses. When relay 11 reenergizes the prepared circuit for relay 14 is completed, and the latter relay at armature 18 completes a circuit for operating the common signals 21, 21', etc., located at different points throughout the establishment over a circuit including the connectors 19 and 20 which are connected to the commercial source of power. Since the first digit dialled is digit 8, the circuit for energizing relay 13 will be intermittently closed eight times in order to maintain relay 13 energized for a period of time equivalent

to a long ring. Since relay 13 at armature 17 controls the circuit of ringing relay 14, it will, therefore, be seen that relay 14 is maintained operated for an interval after relay 13 deenergizes. Therefore, in this case, since the digit 8 was dialled, the ringing relay is maintained operated for a period which corresponds to the long ring, and the common signals, therefore, in response to the first 10 digit, are operated for one long ring. In response to the second digit, or digit 2, the relays respond in the same manner as previously described, only in this case since only two impulses are transmitted the ringing relay 14 will be energized for a shorter interval of time, and, therefore, the common signals will be operated a second time in a short ring. The calling subscriber may continue to dial the code of the desired called subscriber until such party answers. When subscriber S' hears his code of one long and one short ring, subscriber S' will remove the handset from the cradle and complete the desired telephone connection. 15

20 The substation circuit of subscriber S', in response to the removal of the handset from the cradle, is connected to the common conductors 4 and 5, through the spring assembly in the same manner as explained for subscriber S. After conversation, and in response to the replacement of the handsets on their respective cradles the circuit of line relay 11 is opened and said relay deenergizes, thereby deenergizing relay 12. Subscriber 25 S' can call any other local subscriber, such as S, in a manner similar to that described. The other local subscribers' lines (not shown) may also complete local connections in the same manner as just described. 30

35 It will now be assumed that subscriber S desires to originates an outgoing call over trunk No. 1. Subscriber S then removes the handset from the cradle and operates the key TRK #1. In response to the operation of key TRK #1, bar 61 slides in a horizontal direction and operates springs 51, 52, and 56. The substation circuit is now connected to the main exchange over the following circuit: conductor 37, armature 70, multiple trunk 40 conductor 27, resting contact of armature 23 and said armature, conductor 6, working contact of spring 51 and said spring, conductor 2, through the substation circuit, conductor 1, push-button springs 50, conductor 3, springs 56 and 58, armature 24 and its resting contact, trunk multiple conductor 28, armature 71, and conductor 38 to the main exchange. In case trunk No. 1 extends to a manual exchange, subscriber S may operate 45

50 the push-button PB to momentarily open and close the loop to signal the operator at the main exchange in the well known manner. In case trunk No. 1 extends to an automatic exchange, the trunk conductors 37 and 38 55 would terminate in a lineswitch which is operated to automatically select the first numerical switch in the automatic exchange. Subscriber S may thereafter operate the calling device in accordance with the directory number of the desired main exchange subscriber's line to operate the automatic switches in the well-known manner to complete the connection. 60

65 In case subscriber S desires to hold the trunk connection while completing a local connection over the common talking conductors 4 and 5 to another local subscriber in order to receive certain information, subscriber S will thereupon release the key TRK #1, thereby permitting the slide bar 61 to return to its normal position. When slide bar 61 returns to its normal position, springs 51 and 56 also return to their normal positions and connect the substation circuit to the common talking conductors 4 and 5. Springs 52, however, are maintained in operated position by the lock catch 60 to complete a holding circuit over the trunk conductors, as follows: from armature 23, conductor 6, operated springs 52, springs 54, springs 57 and 58, to armature 24 and thence over the multiple trunk connections, as previously traced. Subscriber S then dial rings the code of the desired subscriber and this subscriber, in response to his code ring, will answer and be connected to the common talking conductors 4 and 5. After subscriber S has received the desired information subscriber S will reoperate key TRK #1 to disconnect the substation circuit from the common conductors 4 and 5 and connect the substation circuit to the trunk No. 1 over the circuit previously traced. It might also be stated that if the subscriber S desires another local subscriber to come in on the trunk connection, the subscriber S will complete connection with said subscriber's line and tell him to operate his key TRK #1, whereupon the second subscriber is connected to trunk No. 1 in the same manner as previously described. Subscriber S may also return to this trunk connection by reoperating his trunk key, thereby establishing a three-party connection. 70

75 The connection of the subscriber's line, such as S or S', to trunk No. 2 is somewhat similar to that described for connections to trunk No. 1, only in this case the key TRK #2 is operated to operate the slide bar 60 or 160 to operate the same spring assembly as previously operated by the key TRK #1. In addition, the key TRK #2 operates the springs, such as springs 55 or 155 to complete the circuit for the trunk relays 22 and 30 in the respective subscriber's trunk line circuits. It will be noted that both springs 55 and 155, when operated, are locked in operated position by the locking bars 60 and 160 until the handset is replaced on the cradle. It will be noted that trunk No. 1 is normally connected to the spring assembly in the sub-base by way 80

of resting contacts on relays 22 and 30, and that trunk No. 2 terminates in working contacts of such relays. Therefore, when the relays, such as relays 22 and 30, are energized by key TRK #2 the connections to trunk No. 1 are opened and the trunk No. 2 is connected to the various spring assemblies. With the above description, it is believed that it will be unnecessary to explain the detailed connections for connecting the local subscribers' lines to trunk No. 2, because such connections are the same as previously described with the exception of the operation of relays such as 22 and 30 to select trunk No. 2.

15 It will now be assumed that a main exchange subscriber desires to converse with one of the local subscribers, and in the course of establishing a connection said main exchange subscriber's line has been connected to trunk No. 1, terminating in conductors 37 and 38. When trunk No. 1 is seized at the main exchange, the connector switch thereat transmits ringing current over conductors 37 and 38 in the well-known manner. As previously stated, trunk No. 1 may be equipped with a number of multiple ringers, such as 42, which are located at different points throughout the establishment, or may be provided with an alternating current relay, such as 33, 20 which closes an obvious circuit for lighting the lamps, such as lamp 41, which are located at different points visible to the local subscribers throughout the establishment. Therefore, in response to ringing current, the 25 multiple bells 42 or the colored lamps 41 are lighted to indicate an incoming trunk call. Since there are two trunk lines, the local subscriber must be able to distinguish which trunk line the incoming call is on, and, therefore, the multiple bells 42 are of one tone and the lamps 41 are of a certain color in order to 30 designate trunk No. 1. Any local subscriber in response to the operation of the incoming trunk signal may operate key TRK #1 and 35 complete connection to such trunk line by the operation of the spring assembly in the same manner as described for outgoing calls. In case the incoming call arrives over trunk No. 2, then the multiple bells 43, preferably of a 40 different tone from the bells 42 of trunk No. 1, or the alternating current relays 34 are operated in response to ringing current transmitted from the main exchange. The relay 34, when operated, will close an obvious circuit 45 for operating the lamps 40, which are of a different color from the lamps 41 associated with trunk No. 1. In response to the operation of the signals associated with trunk No. 2, any local subscriber may answer the trunk 50 call by the operation of key TRK #2. By the operation of key TRK #2, relays, such as relays 22 or 30, will be operated to connect the subscriber's line to trunk line No. 2. The local subscriber can hold this trunk line and 55 transfer the call to another local subscriber in

the same manner as previously described. In this system it is, therefore, obvious that there may be as many as three simultaneous connections, that is, there may be one local connection over the common talking conductors, and two trunk connections in progress at the same time.

60 In a system of this kind, it may happen that the executive may wish to talk over one of the trunk lines without danger of any of the other local subscribers overhearing that conversation. The key SS and springs 159 for controlling relays 31 and 32 are provided for this purpose. If the executive desires to hold a secret conversation over the main exchange trunk line when connected thereto, he will then operate the key SS to close springs 159 to operate either relay 31 or 32, dependent upon the trunk line which at this time is connected to the executive's substation circuit. In case the trunk No. 1 is at this time connected to the executive's substation circuit, then relay 32 is operated from ground at springs 159, armature 46 and its resting contact, and through the winding 65 of relay 32, to battery. Relay 32, upon energizing, at armatures 70 and 71 disconnects the trunk multiples 27 and 28 from the trunk conductors 37 and 38 to prevent any other local subscriber from overhearing the conversation. In case the executive was talking over trunk No. 2 instead of trunk No. 1, the operation of key SS completes a circuit for energizing relay 31 instead of relay 32 because at this time relay 30 would have been energized in response to the operation of key TRK #2. By the operation of relay 31, said relay at armatures 48 and 49 disconnects the trunk multiples 25 and 26 from the trunk conductors 35 and 36 to prevent any of the other local subscribers from overhearing the conversation.

65 In order to provide conference calling in a system of this type, it is only necessary that some prearranged code signal, designating a conference call for certain subscribers, be dialed to operate the common signals 21, 21', etc., whereupon all of the local subscribers desired in conference will remove their receivers and be connected to the common conductors 4 and 5.

70 Having described the invention, what is desired to be protected by Letters Patent will be set forth in the following claims.

75 What is claimed is:

1. In a local intercommunicating telephone exchange, a plurality of local subscribers' lines, a pair of talking conductors normally connecting all the local lines together for local telephone service, a plurality of signals common to all said lines, a plurality of trunk lines multiplied to all said subscribers' lines but normally disconnected therefrom, and subscriber controlled means for operating said common signals over said common con- 80

ductors, for completing a local telephone connection between said local lines over said common talking conductors, for answering a trunk call over any one of said trunk lines, 5 and for initiating a trunk call over any desired one of said trunk lines.

2. In a local intercommunicating telephone exchange, a plurality of local subscribers' lines, a pair of talking conductors normally connecting all the local lines together for local telephone service, a plurality of signals common to all said lines, a plurality of trunk lines multiplied to all said subscribers' lines but normally disconnected therefrom, 15 and subscriber controlled means for operating said common signals over said common conductors, for completing a local telephone connection between said local lines over said common talking conductors, for answering a trunk call over any one of said trunk lines, for initiating a trunk call over any desired one of said trunk lines, and for holding a trunk line while making a local connection.

3. In a local intercommunicating telephone exchange, a plurality of local subscribers' lines, a pair of talking conductors normally connecting all the local lines together for local telephone service, a plurality of signals common to all said lines, a plurality of trunk 20 lines multiplied to all said subscribers' lines but normally disconnected therefrom, subscriber controlled means for operating said common signals over said common conductors, for completing a local telephone connection between said local lines over said common talking conductors, for answering a trunk call over any one of said trunk lines, and for initiating a trunk call over any desired one of said trunk lines, and a rectifier 25 connected to a local source of alternating current for producing direct current to provide operating and talking battery to said lines.

4. In a local telephone system, a plurality of local subscribers' lines, a common talking 30 circuit including only a pair of talking conductors normally connecting all said lines for telephone communication, a plurality of signals common to said lines for indicating a call in progress when operated, and means controlled by each subscriber for code ringing the desired one of said lines by simultaneously operating all said common signals over said pair of talking conductors in accordance with the code signal assigned to the desired line.

5. In a local telephone system, a plurality of local subscribers' lines, a common talking circuit normally connecting all said lines for 35 telephone intercommunication, a plurality of signals common to all said lines, means individual to each line for transmitting a plurality of series of impulses over said common talking circuit, all said common signals simultaneously and continuously operated for

the duration of each series of impulses transmitted to code ring a desired subscriber.

6. In a local intercommunicating telephone system, a plurality of local subscribers' lines, a common talking circuit normally connecting said lines for intercommunication, a calling device individual to each line for transmitting a long or a short series of impulses over said talking circuit dependent upon the value of the digit dialled, and a plurality of signals common to all said lines and operated once for each transmitted series of impulses to code ring a desired subscriber by a combination ring in accordance with the value of the digits dialled.

7. In a telephone system, a plurality of subscribers' lines each including a substation circuit, a pair of talking conductors common to all said subscribers' lines, switchhook springs in each substation circuit operated responsive to the removal of the receiver thereat for directly connecting the substation circuit to said common talking conductors, a calling device individual to each substation circuit for transmitting a long or a short series of impulses over said common conductors dependent upon the value of the digit dialled on the operation of the calling device, and a plurality of signals common to all said lines operated in response to each operation of the calling device to code ring a desired subscriber by a combination of short or long rings or both dependent upon the value of the digits dialled on successive operations of the calling device.

8. In a telephone system, a local exchange and a distant exchange, a plurality of subscribers' lines in said local exchange, a common talking circuit normally connecting all said subscribers' lines for local communication within the local exchange, a plurality of signals common to all said subscribers' lines, a plurality of trunk lines connecting the local exchange with said distant exchange, said trunk lines common to all said subscribers' lines but normally disconnected therefrom, means individual to each subscriber's line for enabling the subscriber thereat to disconnect his line from said common talking circuit and connect his line to any desired one of said trunk lines, for enabling the subscriber to thereafter disconnect his line from said trunk line and connect his line to said common talking circuit without releasing said trunk line, means controlled by said subscriber for dial ringing said common signals over said common talking circuit to code ring a desired subscriber, means responsive to the desired called subscriber's answering

from any local subscriber's line for connecting this subscriber's line to said common talking circuit to complete a local talking circuit between the two subscriber's to enable the first subscriber to tell the second subscriber that he is wanted on a certain trunk

line, and said individual means at the answering subscriber's line operated by the called subscriber to disconnect said answering subscriber's line from said common talking circuit and connect such line to the held trunk line to complete the connection desired on said trunk line.

9. In a telephone system, a local exchange and a distant exchange, a plurality of subscribers' lines in said local exchange, a common talking circuit provided for local telephone communication between subscribers within the local exchange, switching means individual to each subscriber's line for normally connecting said common talking circuit to each subscriber's line, a plurality of trunk lines connecting the local exchange with said distant exchange, said trunk lines terminating in each individual switching means but normally disconnected from the subscribers' lines, a key individual to each trunk line at each subscriber's line for controlling said switching means, the individual switching means at any one of said subscribers' lines, operated responsive to the operation of any one of said individual keys thereat for disconnecting said subscriber's line from said common talking circuit and for connecting said subscriber's line to the trunk line corresponding to the operated key, said switching means operated responsive to the restoration of said operated key for providing a holding circuit for said trunk line, for disconnecting said subscriber's line from said trunk line and for connecting said subscriber's line to said common talking circuit in case some other subscriber is desired on said trunk line, signals common to all said local subscribers' lines, means controlled by said subscriber for transmitting a plurality of series of impulses over said common talking circuit to code ring said common signals in accordance with the duration of each series transmitted and in accordance with the code ring of the desired other subscriber, means responsive to the called subscriber's answering at any local subscriber's line for connecting this subscriber's line to said common talking circuit to complete a talking circuit between the two subscribers to enable the first subscriber to tell the called subscriber that he is wanted on a certain trunk line, and the individual switching means at said second subscriber's line operated responsive to the operation of the proper trunk key for disconnecting the second subscriber's line from said common talking circuit and for connecting the second subscriber's line to the held trunk line to complete the desired connection over said trunk line.

10. In a telephone system, a subscriber's line, other subscribers' lines, a pair of talking conductors normally connecting said subscriber's line with all of said other subscrib-

ers' lines, a pair of springs individual to said line and controlled by said subscriber, a plurality of trunk lines, means responsive to a call by the subscriber on said line and the operation of said springs for establishing a connection between said subscriber's line and one of said trunk lines, means for locking said springs in operated position, a holding circuit including said springs for holding an established trunk connection over any of said trunk lines, and means for establishing said holding circuit while completing a local talking connection over said pair of common talking conductors to said other subscribers' lines.

11. In a telephone system, a subscriber's line, sets of springs individual to said line, a first and a second trunk key controlled by said subscriber for controlling said springs, a trunk line circuit individual to said line and connected to said springs, a first and a second trunk line terminating in said individual trunk line circuit, means responsive to the operation of either key and said springs by the subscriber for establishing a connection between said subscriber's line and the trunk line corresponding to the operated key by way of said trunk line circuit, means for automatically locking a certain set of said springs in response to their initial operation, a holding circuit including said certain set of locked springs for holding an established trunk connection, means responsive to the restoration of said operated key for restoring all said springs except said locked springs to establish said holding circuit, and means for unlocking said certain set of springs responsive to the replacement of the receiver by the subscriber.

12. In a telephone system, a plurality of local subscribers' lines, sets of springs individual to and terminating each subscriber's line, a pair of common talking conductors normally connected to each subscriber's line by way of said sets of springs, a trunk line circuit individual to each subscriber's line and terminating in said individual sets of springs, a first and a second trunk line each terminating in each individual trunk line circuit, a corresponding first and second trunk line key individual to each subscriber's line for controlling the individual sets of springs, means responsive to the operation of either key and said springs at one of said subscriber's lines for disconnecting said subscriber's line from said normally connected common talking conductors and for establishing a connection between said subscriber's line and the trunk line corresponding to the operated key by way of the associated individual trunk line circuit, means for automatically locking a certain set of said individual operated springs in response to their initial operation by either of said keys, a holding circuit for each subscriber's line including said certain set of locked springs for holding an established

- trunk line connection, means responsive to the restoration of the operated key for restoring all said operated springs except said locked springs to establish said holding circuit, and means for unlocking said certain locked set of springs responsive to the replacement of the receiver by the subscriber. 5
13. In a telephone system, a plurality of local subscribers' lines, sets of springs individual to and terminating each subscriber's line, a pair of common talking conductors normally connected to each subscriber's line by way of said sets of springs, a trunk line circuit individual to each subscriber's line 10 and terminating in said individual sets of springs, a first and a second trunk line each terminating in each individual trunk line circuit, a corresponding first and second trunk line key individual to each subscriber's line 15 for controlling the individual sets of springs, means responsive to the operation of either key and said springs at one of said subscriber's lines for disconnecting said subscriber's line from said normally connected common 20 talking conductors and for establishing a connection between said subscriber's line and the trunk line corresponding to the operated key by way of the associated individual trunk line circuit, means for automatically locking 25 a certain set of said individual operated springs in response to their initial operation by either of said keys, a holding circuit for each subscriber's line including said certain set of locked springs for holding an established 30 trunk line connection, means responsive to the restoration of the operated key for restoring all said operated springs except said locked springs to establish said holding circuit, means for unlocking said certain 35 locked set of springs responsive to the replacement of the receiver by the subscriber, means responsive to the restoration of the operated key for restoring all said operated springs except said locked springs to establish said holding 40 circuit for said connected trunk line and to reconnect the subscriber's line with said common talking conductors, a set of signals common to all said subscribers' lines, means controlled by said subscriber for 45 transmitting a plurality of series of impulses over said common talking conductors to operate said common signals to code ring a desired subscriber in accordance with the length of each impulse series, means responsive to 50 the called subscriber answering for completing a talking circuit over said common talking conductors and the individual spring sets and the calling and called subscribers' lines, and means whereby either subscriber by the 55 operation of the trunk key corresponding to the held trunk line may operate their individual spring sets to connect their lines with the said held trunk line by way of their individual trunk line circuits. 60
14. In a telephone system, local subscribers' lines each comprising a local line circuit normally connected to each other over a pair of common talking conductors, a trunk line circuit, a substation circuit, a spring assembly for connecting the substation circuit to either the trunk line circuit or the local line circuit, and a first and second trunk key for controlling said spring assembly, a plurality of two-way interexchange trunk lines terminating in each trunk line circuit, means responsive to the operation of the first trunk key at one of the subscribers' lines for operating the spring assembly thereat and for connecting the subscriber's substation circuit to the first of said trunk lines by way of the associated trunk line circuit, means responsive to the operation of the second trunk key at said subscriber's line for operating said spring assembly thereat and for connecting the subscriber's substation circuit to the second trunk line by way of said associated trunk line circuit, and a holding circuit included in said spring assembly for holding a trunk connection by way of said trunk line circuit when an operated trunk key is restored to normal. 65
15. In a telephone system, local subscribers' lines each comprising a trunk line circuit, a substation circuit, a spring assembly for connecting the substation circuit to the trunk line circuit, and a pair of keys either one of which controls the operation of said spring assembly, a pair of common talking conductors normally connecting all the substation circuits of all the subscribers' lines to each other by way of said spring assemblies, a relay having normally open and normally closed contacts in each trunk line circuit, a first trunk line multiplied between said trunk line circuits and connected to each spring assembly by way of said normally closed contacts on said relays, a second trunk line multiplied between said trunk line circuits and connected to said normally open contacts on said relays, means for establishing local telephone connections between said local lines over said pair of common talking conductors and the associated spring assemblies, means for disconnecting said substation circuits from said pair of common talking conductors and for connecting the substation circuits to their associated trunk line circuits in response to the operation of either of said associated keys, and means for operating the relay of the associated trunk line circuit only in case a certain one of said keys is operated to connect said second trunk line to the substation circuits by way of said normally open contacts and said spring assembly in place of said first trunk line. 70
16. In a local intercommunicating telephone exchange, a plurality of local subscribers' lines and a local executive's line, a trunk line circuit individual to each of said lines but normally disconnected there- 75

from, a plurality of trunk lines extending from a distant exchange terminating in the executive's trunk line circuit, a multiple connection for each of said trunk lines connecting the trunk line circuits of each of said plurality of lines with the trunk line circuit of said executive's line, connecting means in the executive's trunk line circuit normally connecting said multiple connections to their respective trunk lines, subscriber controlled means individual to each of said plurality of subscribers' lines for connecting such lines at will to any desired one of said trunk lines by way of their trunk line circuits, said multiple connections, and said connecting means, subscriber controlled means individual to said executive's line for connecting said line at will to any desired one of said trunk lines by way of its trunk line circuit, and additional subscriber controlled means at only the executive's line for operating said connecting means to disconnect any desired one of said trunk lines from its associated multiple connections at the will of the executive.

17. In a local intercommunicating telephone exchange, a plurality of local subscribers' lines and a local executive's line, a trunk line circuit individual to each of said lines but normally disconnected therefrom, a plurality of trunk lines extending from a distant exchange terminating in the executive's trunk line circuit, a multiple connection for each of said trunk lines connecting the trunk line circuits of each of said plurality of lines with the trunk line circuit of said executive's line, connecting means in the executive's trunk line circuit normally connecting said multiple connections to their respective trunk lines, a trunk key for each of said trunk lines at each of said plurality of subscribers' and executive's lines, means responsive to the operation of a trunk key at any one of said plurality of subscribers' lines for connecting such lines to the trunk line corresponding to the operated trunk key by way of their individual trunk line circuits, the corresponding trunk multiple connections, and said connecting means, means responsive to the operation of a trunk key at said executive's line for connecting such line to the trunk line corresponding to the operated trunk key by way of the executive's individual trunk line circuit, and a special key on only said executive's line for operating said connecting means to disconnect but one of said trunk lines at a time from its said trunk multiple connections, the particular one trunk line being disconnected from its multiple connections by the operation of said connecting means being dependent upon which one of said trunk keys is operated at the executive's line.

18. In a telephone system, local subscribers' lines and an executive's line each comprising a substation circuit and a trunk line circuit, a pair of common talking conductors, a spring

assembly individual to each line normally connecting all the substation circuits together over said common talking conductors and for operatively connecting said substation circuits to the trunk line circuits, a first and a second trunk key individual to each line for controlling said spring assembly, a first and a second trunk line terminating in the executive's trunk line circuit, multiple connections for each trunk line connecting all the local trunk line circuits to the executive's trunk line circuit, connecting means in said executive's trunk line circuit normally connecting said multiple trunk connections to their respective trunk lines, means responsive to the operation of either one of said trunk keys at said local or executive's lines for operating said spring assembly thereat to disconnect the substation circuit from said common talking conductors and for connecting the substation circuit to the trunk line corresponding to the operated trunk key by way of said trunk line circuit, said multiple trunk connections, and said connecting means, and a third key at said executive's line for operating said connecting means to disconnect but one trunk line at a time from its associated trunk multiple connections, the particular trunk line being disconnected from its multiple connections by the operation of said connecting means being dependent upon which one of said trunk keys is operated at the executive's line.

In witness whereof, I hereunto subscribe my name this 15th day of October, A. D. 1931.

JOHN H. VOSS.
